UNITED STATES PATENT OFFICE.

WILLIAM W. ANDERSON, OF CHICAGO, ILLINOIS.

COMBINED TABLE AND IRONING-BOARD.

1,342,660.

Specification of Letters Patent.

Patented June 8, 1920.

Application filed October 18, 1919. Serial No. 331,640.

To all whom it may concern:

Be it known that I, WILLIAM W. ANDERSON, a citizen of the United States, residing at Chicago, in the county of Cook and State of Illinois, have invented certain new and useful Improvements in Combined Table and Ironing-Board, of which the following is a specification.

This invention relates to tables and its object is to provide a table having a top carrying an ironing board, the top being reversible so that in one position it serves as an ordinary top for the table, whereas in another position it serves as an ironing board.

15 The invention also has for its object to provide a very simple structure of the kind stated.

With the objects stated in view, the invention consists in a novel combination and arrangement of parts to be hereinafter described and claimed, and in order that the same may be better understood, reference is had to the accompanying drawings forming a part of this specification.

25 In the drawings,

Figure 1 is a perspective view of the table showing the ironing board positioned for use, and

Fig. 2 is a longitudinal section of the table showing the top thereof in another position.

Referring specifically to the drawings, the table is composed of a top 10 seating on side and end rails 11 and 12, respectively, and legs 13 secured to said rails in any approved manner. Except as hereinafter noted, the table resembles a kitchen table of conventional design.

The top 10 carries an ironing board 14 which is secured to the under side thereof in any suitable manner. The ironing board is so dimensioned that it seats inside the rails 11 and 12 of the table when the top 10 is in place and serving its ordinary function.

40 The top 10 is not permanently attached to the rails 11 and 12 but seats loosely thereon, so that it may be lifted off and reversed to place the ironing board 14 uppermost, and thus position it for use, as shown in Fig. 1. The top is now still supported by

the rails, and it serves as a supporting base 50 for the ironing board.

To hold the top 10 in place in the last-described position, it is provided with eyes 15 adjacent to its ends, said eyes being positioned to receive hooks 16 on the end rails 55 12. Upon disengaging the hooks from the eyes, the top can be lifted and replaced on the rails 11 and 12 in inverted position, the ironing board being now underneath and seating inside the rails. The top now has 60 the function of an ordinary table top, and the ironing board is completely concealed and hidden from view. Fig. 2 shows the parts in this position.

In the last described position of the top 65 10, the ironing board 14 seats snugly between the end rails 12, and thus serves to prevent the top from shifting out of place, so that no fastening devices are necessary for securing the top against displacement. 70 The weight of the top and the parts carried thereby also tend to hold the same down firmly on the side and end rails.

I claim:

1. A table comprising side and end rails, 75 legs extending from said rails, a reversible top loosely seating on the side and end rails, and an ironing board carried by the top on one side thereof, and fitting between the side and end rails and in engagement with the 80 latter rails in one position of the top, and being above the top when the latter is reversed.

2. A table comprising side and end rails, legs extending from and supporting said 85 rails, a top provided with an unbroken face on one side thereof and removably seated on said rails, and an ironing board secured to said top in spaced relation thereto to be positioned below said top and between said 90 rails, when said top is seated with said unbroken face forming the upper side thereof, and positioned above when said top is seated with said unbroken face forming the under side thereof.

95 In testimony whereof I affix my signature.

WILLIAM W. ANDERSON.
